UNITED STATES PATENT OFFICE.

JOSEPH T. BAILEY, OF PHILADELPHIA, PENNSYLVANIA.

DESIGN FOR A BADGE.

SPECIFICATION forming part of Design No. 30,931, dated June 6, 1899.

Application filed May 5, 1899. Serial No. 715,743. Term of patent 14 years.

To all whom it may concern:

Be it known that I, JOSEPH T. BAILEY, a citizen of the United States, residing in the city and county of Philadelphia, State of Pennsylvania, have invented and produced a new and original Design for a Badge, of which the following is a specification, reference being had to the accompanying drawings, forming part thereof.

10 The leading feature of my design for a badge is the representation of a cross-shaped figure with representations of cannons, an anchor, and a seal on the face thereof.

15 Figures 1 and 2 represent views of the obverse and reverse of a badge embodying my design.

In the drawings, A designates the repre-

sentation of a cross-shaped figure, on the obverse of which are the representations of cross-cannons B, an anchor C, and a central seal D. 20 Surmounting the figure A is the representation of an eagle E. On the reverse there is a representation of a central seal F and a shield G in said seal.

Having thus described my invention, what 25 I claim as new, and desire to secure by Letters Patent, is—

The design for a badge substantially as shown and described.

JOS. T. BAILEY.
